Patented July 19, 1960

188,432

COMBINED JUICER AND PITCHER

Jean O. Reinecke, Los Angeles, Calif., assignor to The Plas-Tex Corporation, Los Angeles, Calif., a corporation of California

Filed Jan. 12, 1960, Ser. No. 59,022

Term of patent 14 years

(Cl. D44—21)

I claim:

The ornamental design for a combined juicer and pitcher, substantially as shown.
